APPARATUS FOR CLEANING GUN BARRELS

Harry K. Cooper, Gardena, Calif.

Application August 20, 1948, Serial No. 45,332

9 Claims. (Cl. 134—99)

(Granted under the act of March 3, 1883, as
amended April 30, 1928; 370 O. G. 757)

1

This invention relates to apparatus for cleaning gun barrels and more particularly to apparatus to facilitate removing copper deposits from that type of gun barrel which is large, cumbersome, and difficult to dismantle.

Heretofore, various devices and methods have been used in an attempt to safely and rapidly remove copper deposited in the bores of large calibre gun barrels. Such schemes include mechanical tools, special decoppering charges fired from the gun, leaded ammunition, wire brushing, and lapping. However, there are many attendant disadvantages in the use of the above mentioned devices and methods. In the use of mechanical means, such as broaches, reamers, etc., there is the obvious danger of injury to the rifling of the gun barrels. To minimize this danger, the process must of necessity be very slow. Disadvantages of the decoppering charges and of the leaded ammunition are the high cost of producing these items and the added factor of expendability. Another disadvantage of these methods is that the gun barrel must be mounted and in condition for use. Lapping and wire brushing to remove copper deposits are of their very nature slow and tedious and are therefore limited in use to guns which are dismantled or in the repair shops.

It is an object of this invention to provide an apparatus for cleaning and removing copper deposits from gun barrels without the attendant disadvantages of the prior methods and devices.

Another object of this invention is to provide an apparatus which can be used to clean and decopper gun barrels without removing the barrels from the gun.

Another object of this invention is to provide an apparatus for decoppering gun barrels which requires no great skill on the part of the operator.

Another object of this invention is to provide an apparatus for decoppering gun barrels which is rapid in action and which cannot injure the rifling of the gun barrel.

A further object of this invention is to provide an apparatus wherein the decoppering of a gun barrel is accomplished with dispatch and at relatively small cost.

Other objects and many of the attendant advantages of this invention will be readily appreciated as the same becomes better understood by reference to the following description.

The apparatus of this invention comprises generally a pair of elongate tanks which contain, respectively, cleaning liquid and neutralizer. The tanks are secured together by a front mounting member having at its bottom an inverted saddle

portion formed so as to seat over a gun barrel near its discharge end. A saddle shaped clamping plate disposed beneath the gun barrel and abutting the mounting member to which it is bolted serves to clamp the tanks to the discharge end of the barrel.

A rear, or breech, mounting plate is secured transversely beneath said tanks, the breech mounting plate having an inverted saddle for seating over the barrel near its breech. A U clamp is secured to the breech mounting plate and coacts with the breech saddle to clamp the tanks to the breech end of the barrel. An expandible plug is provided for sealing the breech end of the barrel during the cleaning operation.

A cover plate to close the discharge end of the barrel is bolted to the clamping plate and front mounting member to effectively seal the gun barrel and retain liquid. A tube, serving as a liquid inlet conduit, extends through the cover plate at its center, and terminates within the barrel near the breech end. This inlet tube communicates by means of inlet conduits with the pair of tanks near their respective bottoms. An air inlet conduit is connected to the liquid inlet and serves selectively to agitate the liquid or eject it from within the barrel into the tanks. A valve is provided in the air conduit to permit increase or decrease of air flow.

Near the top of the cover plate is located an air vent conduit which extends above the liquid level in the barrel and which can be closed by means of a valve. At the bottom of the cover plate is an outlet conduit communicating with the pair of tanks near their respective tops, which serves to return the liquid thereto. Suitable valves are provided in both the inlet and outlet conduits for selectively connecting either of the tanks to either feed liquid to or receive liquid from the barrel.

In operation, the gun breech is sealed with the plug. Cleaning liquid is permitted to flow into the barrel from the cleaning liquid tank through the inlet conduit communicating with the bottom of the tank and the inlet tube within the barrel. At this point, the return conduit to the cleaning tank is closed, and both the inlet and return conduit of the neutralizer tank are closed, while the air vent is opened to the atmosphere. Gravity flow of cleaning liquid fills the gun barrel and a stream of air is introduced through the inlet tube to agitate the cleaning liquid within the barrel. The agitating air escapes from the barrel through the vent conduit. The cleaning liquid is permitted to remain in the barrel with constant air agi-

tation for periods of time proportional to the thickness of the copper coating to be removed.

Upon completion of the decoppering period, the vent conduit is closed to the atmosphere, the inlet conduit is closed, and the return conduit from the bottom of the cover plate to the top of the cleaning liquid tank is opened. Air from the air conduit builds up pressure in the gun barrel and thereby forces the cleaning liquid out of the barrel through the return conduit and through a filter in the top of the cleaning liquid tank. Both tanks are vented to the atmosphere to prevent pressure build-up. The return phase of the cycle can be accelerated by increasing the air flow into the barrel.

When the cleaning liquid has been expelled, the return conduit to the cleaning tank is closed and the vent conduit is again opened to the atmosphere. The inlet conduit from the neutralizing tank is opened. Neutralizing liquid is permitted to flow into the barrel and a cycle similar to that of the cleaning cycle is effected. When the neutralizer has been returned to its tank, the cover plate is loosened, the expansible plug is removed, and upon removal of the clamping plate and U bolt from the front and rear mounting members, respectively, the apparatus can be readily removed from the gun barrel.

A preferred embodiment of the instant invention has been illustrated in the accompanying drawing, wherein:

Fig. 1 is a perspective view of the instant invention showing it mounted on a gun barrel;

Fig. 2 is a diagrammatic representation of the instant invention to illustrate the flow of liquids; and

Fig. 3 is an enlarged, partial sectional view taken on line 3-3 of Fig. 1.

Referring to Fig. 1 of the drawing, numerals 11 and 12 designate a tank for cleaning liquid and a tank for neutralizer liquid, respectively. The tanks 11 and 12 are secured together by a front mounting member 13 having at its bottom an inverted saddle portion 14 formed so as to seat over a gun barrel 15 near its discharge end. A saddle shaped clamping plate 16 disposed beneath the gun barrel 15 and abutting the mounting member 13 to which it is bolted, serves to clamp the tanks 11 and 12 to the discharge end of the barrel 15. A rear mounting member 17 having a saddle portion 18 and a hoop 19 engages the barrel adjacent its midsection.

An expansible plug 21 is provided for sealing the breach end of the barrel during the cleaning and neutralizing operation. In the preferred embodiment of the plug is adapted from a dummy shell of a suitable size.

A cover plate 22 is provided to close the discharge end of the barrel and is bolted to the clamping plate 16 and the front mounting member 13 to seal the gun barrel against escape of liquid. A tube 23, serving as a liquid inlet conduit, extends through the cover plate 22 at its center, and terminates within the barrel 15 near the breach end. Inlet tube 23 is provided with a plurality of spacing lugs 24, which keeps it centered within the bore of the barrel 15. The inlet tube 23 communicates by means of inlet conduits 25 and 26 with the bottoms of the tanks 11 and 12, respectively. Valves 27 and 28 are provided in the conduits 25 and 26, respectively, for selectively connecting either of the tanks 11 or 12 to feed liquid to the barrel 15.

An air inlet conduit 29 from a source of air under pressure (not shown) is connected to the

liquid inlet, and serves to introduce agitating and expelling air into the barrel. A valve 31 is provided in the air conduit 29 to permit increase or decrease of air flow into the barrel.

5 Near the top of the cover plate 22 is located an air vent conduit 32 which extends above the liquid level in the barrel and which can be closed to the atmosphere by means of a valve 33. At the bottom of the cover plate 22 is an outlet conduit 34 communicating by means of the outlet conduits 35 and 36 with the tanks 11 and 12, respectively, at their tops. The outlet conduits 35 and 36 serve to return the liquid to the respective tanks. Suitable valves 37 and 38 are provided in the conduits 35 and 36, respectively, for selectively connecting either of the tanks to receive liquid from the barrel.

10 At the top of the tanks the outlet conduits 35 and 36 discharge the liquid into the filter chambers 39 and 41, respectively, where the liquid is filtered by a screen 42 (Fig. 3). Air vents 43 are provided in each tank to prevent pressure build-up in the tanks.

Operation

15 In operation, the breech is first sealed with the plug 21. Valve 27 is opened and cleaning liquid is then permitted to flow into the gun barrel 15 from the cleaning tank 11 through the inlet conduit 25 communicating with the bottom of the tank and the inlet tube 23 within the barrel 15. At this time, the valve 37 of the cleaning liquid return conduit 35 is closed, and both the inlet valve 28 and the return valve 38 of the neutralizer tank are closed, while the air vent 32 is opened to the atmosphere. Gravity flow of cleaning liquid fills the gun barrel and a stream of air is introduced from the air conduit 29 through the inlet tube 23 to agitate the cleaning liquid within the barrel. The surplus agitating air escapes from the barrel 15 through the vent conduit 32. The cleaning liquid is permitted to remain in the barrel with constant air agitation for periods of time proportional to the thickness of the coating to be removed.

20 Upon completion of the decoppering period, the vent conduit 32 is closed to the atmosphere by means of the valve 33, the inlet conduit 25 is closed by means of the valve 27, and the return conduit 35 from the outlet conduit 34 at the bottom of the cover plate 22 to the top of the cleaning tank 11 is opened by means of the valve 37. Air from the air conduit 29, by building up pressure in the gun barrel, displaces and thereby forces the cleaning liquid out of the barrel 15 through the return conduits 34 and 35 into the filter chamber 39 through the filter 42 and into the cleaning fluid tank 11. The return phase of the cycle can be accelerated by increasing, by means of the valve 31, the air flow into the barrel.

25 When the cleaning liquid has been expelled, the return conduit 35 to the cleaning tank is closed and the vent conduit 32 is again opened to the atmosphere. The inlet conduit 26 from the neutralizing tank is opened by means of the valve 28. Neutralizing liquid is permitted to flow into the barrel where it is agitated and returned to the tank 12 in a cycle similar to that of the cleaning cycle.

30 After the neutralizer has been returned to its tank 12, the cover plate 22 is loosened, the expansible plug 21 is removed, and upon removal of the clamping plate 16 and U clamp 19 from the front and rear mounting members 13 and 17, respectively, the apparatus can be removed from the gun barrel.

Obviously many modifications and variations of the present invention are possible in the light of the above teachings. It is therefore to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed is:

1. Apparatus for cleaning gun barrels comprising a pair of elongate tanks adapted to contain, respectively, cleaning liquid and neutralizer, a front mounting member secured transversely beneath said tanks having therebelow an inverted saddle portion adapted to seat over a gun barrel near the discharge end thereof, a saddle shaped clamping plate adapted to be disposed beneath the barrel and said portion, means for securing said plate to said portion thereby to clamp said tanks to the discharge end of the barrel, a cover plate adapted to close the discharge end of the barrel, bolting means extending between said cover plate and said clamping plate and saddle portion effective to clamp said cover plate over the end of the barrel to contain liquid therein, a liquid inlet conduit extending through said cover plate at its center, adapted to terminate within the barrel near the breech thereof, and communicating with said tanks near their respective bottoms, an air inlet conduit connected to said liquid inlet conduit for injecting agitating air into the liquid in the barrel, valve means in said air inlet conduit, an air vent conduit extending through said cover plate near the top thereof and being open to atmosphere at a point above the barrel, valve means in said air vent conduit, an outlet conduit extending through said cover plate near the bottom thereof and communicating with said tanks near the respective tops thereof, valve means disposed in said inlet and outlet conduits for selectively connecting either of said tanks to feed liquid to or receive liquid from the barrel, a breech mounting member secured transversely beneath said tanks having therebelow an inverted saddle portion adapted to seat over the gun barrel near the breech thereof, a U clamp secured to said breech saddle for clamping said tanks to the breech end of the barrel, and an expansible plug for sealing the breech end of the barrel during the cleaning operation.

2. Apparatus for cleaning gun barrels comprising a pair of elongate tanks adapted to contain, respectively, cleaning liquid and neutralizer, a front mounting member secured transversely beneath said tanks having therebelow an inverted saddle portion adapted to seat over a gun barrel near the discharge end thereof, a saddle shaped clamping plate adapted to be disposed beneath the barrel and said portion, means for securing said plate to said portion thereby to clamp said tanks to the discharge end of the barrel, a cover plate adapted to close the discharge end of the barrel to contain liquid therein, a liquid inlet conduit extending through said cover plate at its center, adapted to terminate within the barrel near the breech thereof, and communicating with said tanks, an air inlet conduit communicating with the liquid inlet conduit for injecting agitating air into the liquid in the barrel, an air vent conduit extending through said cover plate near the top thereof and being open to atmosphere at a point above the barrel, an outlet conduit extending through the cover plate and communicating with said tanks, valve means disposed in said inlet and outlet conduits for selectively connecting either of said tanks to feed liquid to or receive liquid from the barrel, and a plug for sealing the breech end of the barrel during the cleaning operation.

an outlet conduit extending through the cover plate and communicating with said tanks, valve means disposed in said inlet and outlet conduits for selectively connecting either of said tanks to feed liquid to or receive liquid from the barrel, a breech mounting member secured transversely beneath said tanks having therebelow an inverted saddle portion adapted to seat over the gun barrel near the breech thereof, a U clamp secured to said breech saddle for clamping said tanks to the breech end of the barrel, and an expansible plug for sealing the breech end of the barrel during the cleaning operation.

3. Apparatus for cleaning gun barrels comprising a pair of elongate tanks adapted to contain, respectively, cleaning liquid and neutralizer, a front mounting member secured transversely beneath said tanks having therebelow an inverted saddle portion adapted to seat over a gun barrel near the discharge end thereof, a saddle shaped clamping plate adapted to be disposed beneath the barrel and said portion, means for securing said plate to said portion thereby to clamp said tanks to the discharge end of the barrel, a cover plate adapted to close the discharge end of the barrel to contain liquid therein, a liquid inlet conduit extending through said cover plate, adapted to terminate within the barrel near the breech thereof, and communicating with said tanks, an air inlet conduit communicating with the liquid inlet conduit for injecting agitating air into the liquid in the barrel, an air vent conduit extending through said cover plate near the top thereof and being open to atmosphere at a point above the barrel, an outlet conduit extending through the cover plate and communicating with said tanks, valve means disposed in said inlet and outlet conduits for selectively connecting either of said tanks to feed liquid to or receive liquid from the barrel, and a plug for sealing the breech end of the barrel during the cleaning operation.

4. Apparatus for cleaning gun barrels comprising a pair of elongate tanks adapted to contain, respectively, cleaning liquid and neutralizer, means for securing said tanks to the barrel, a cover plate adapted to close the discharge end of the barrel to contain liquid therein, a liquid inlet conduit adapted to terminate within the barrel near the breech thereof and communicating with said tanks, an air inlet conduit communicating with the liquid inlet conduit for injecting agitating air into the liquid in the barrel, an air vent conduit extending through said cover plate near the top thereof and being open to atmosphere at a point above the barrel, an outlet conduit extending through the cover plate and communicating with said tanks, valve means disposed in said inlet and outlet conduits for selectively connecting either of said tanks to feed liquid to or receive liquid from the barrel, and a plug for sealing the breech end of the barrel during the cleaning operation.

5. Apparatus for cleaning gun barrels comprising an elongate tank adapted to contain cleaning liquid, a front mounting member secured transversely beneath said tank having therebelow an inverted saddle portion adapted to seat over a gun barrel near the discharge end thereof, a saddle shaped clamping plate adapted to be disposed beneath the barrel and said portion, means for securing said plate to said portion thereby to clamp said tank to the discharge end of the barrel, a cover plate adapted to close the discharge end of the barrel, bolting means ex-

tending between said cover plate and said clamping plate and saddle portion effective to clamp said cover plate over the end of the barrel to contain liquid therein, a liquid inlet conduit extending through said cover plate at its center, adapted to terminate within the barrel near the breech thereof, and communicating with said tank near the bottom thereof, an air inlet conduit connected to said liquid inlet conduit for injecting agitating air into the liquid in the barrel, valve means in said air inlet conduit, an air vent conduit extending through said cover plate near the top thereof and being open to atmosphere at a point above the barrel, valve means in said air vent conduit, an outlet conduit penetrating said cover plate near the bottom thereof and communicating with said tank near the top thereof, valve means disposed in said inlet and outlet conduits for selectively connecting said tank to feed liquid to or receive liquid from the barrel, a breech mounting member secured transversely beneath said tank having therebelow an inverted saddle portion adapted to seat over the gun barrel near the breech thereof a U clamp secured to said breech saddle for clamping said tank to the breech end of the barrel, and an expandable plug for sealing the breech end of the barrel during the cleaning operation.

6. Apparatus for cleaning gun barrels comprising an elongate tank adapted to contain cleaning liquid, a front mounting member secured transversely beneath said tank having therebelow an inverted saddle portion adapted to seat over a gun barrel near the discharge end thereof, a saddle shaped clamping plate adapted to be disposed beneath the barrel and said portion, means for securing said plate to said portion thereby to clamp said tank to the discharge end of the barrel, a cover plate adapted to close the discharge end of the barrel to contain liquid therein, a liquid inlet conduit adapted to terminate within the barrel near the breech thereof and communicating with said tank, an air inlet conduit communicating with the liquid inlet conduit for injecting agitating air into the liquid in the barrel, an air vent conduit extending through said cover plate near the top thereof and being open to atmosphere at a point above the barrel, an outlet conduit extending through the cover plate and communicating with said tank, valve means disposed in said inlet and outlet conduits for alternatively connecting said tank to feed liquid to or receive liquid from the barrel, a breech mounting member secured transversely beneath said tank having therebelow an inverted saddle portion adapted to seat over the gun barrel near the breech thereof a U clamp secured to the breech saddle for clamping said tank to the breech end of the barrel, and a plug for sealing the breech end of the barrel during the cleaning operation.

7. Apparatus for cleaning gun barrels comprising an elongate tank adapted to contain cleaning liquid, a front mounting member secured transversely beneath said tank having therebelow an inverted saddle portion adapted to seat over a gun barrel near the discharge end thereof, a saddle shaped clamping plate adapted to be disposed beneath the barrel and said portion, means for securing said tank to the barrel, a cover plate adapted to close the discharge end of the barrel to contain liquid therein, a liquid inlet conduit adapted to terminate within the barrel near the breech thereof and communicat-

ing with said tank, an air inlet conduit communicating with the liquid inlet conduit for injecting agitating air into the liquid in the barrel, an air vent conduit extending through said cover plate near the top thereof and being open to atmosphere at a point above the barrel, an outlet conduit extending through the cover plate and communicating with said tank, valve means disposed in said inlet and outlet conduits for alternatively connecting said tank to feed liquid to or receive liquid from the barrel, and a plug for sealing the breech end of the barrel during the cleaning operation.

8. Apparatus for cleaning gun barrels comprising an elongate tank adapted to contain cleaning liquid, means for securing said tank to the barrel, a cover plate adapted to close the discharge end of the barrel to contain liquid therein, a liquid inlet conduit adapted to terminate within the barrel near the breech thereof and communicating with said tank, an air inlet conduit communicating with the liquid inlet conduit for injecting agitating air into the liquid in the barrel, an air vent conduit extending through said cover plate near the top thereof and being open to atmosphere at a point above the barrel, an outlet conduit extending through the cover plate and communicating with said tank, valve means disposed in said inlet and outlet conduits for alternatively connecting said tank to feed liquid to or receive liquid from the barrel, and a plug for sealing the breech end of the barrel during the cleaning operation.

9. Apparatus for cleaning the bore of a cannon barrel, comprising a liquid container, clamping means for engaging the barrel to secure the container thereto, a cover plate for closing the cannon muzzle, a liquid inlet conduit communicating with said tank and adapted to extend within the bore and terminate near the cannon breech, an air inlet conduit communicating with the liquid inlet conduit for injecting air into the bore, an air vent conduit extending thru the upper portion of the cover plate and terminating at a point above the barrel, an outlet conduit extending thru the cover plate and communicating with said tank for returning liquid from the bore to said tank, and valve means for alternatively connecting said tank to feed liquid or to receive liquid from the bore.
